UNITED STATES PATENT OFFICE.

EDWIN E. SMEETH, OF CHICAGO, ILLINOIS.

METHOD OF CASTING HOLLOW ARTICLES.

Application filed December 22, 1924. Serial No. 757,497.

To all whom it may concern:

Be it known that I, EDWIN E. SMEETH, a citizen of the United States, and a resident of Chicago, in the county of Cook and State of Illinois, have invented certain new and useful Improvements in Methods of Casting Hollow Articles, of which the following is a specification, reference being had to the accompanying drawings.

My invention relates to the casting of hollow articles such as bosh plates for furnaces, and has for its object to provide a new and improved method of casting such bosh plates or other analogous hollow articles by which the necessity of using anchors or chaplets to properly position the core will be avoided. I accomplish this object as illustrated in the drawings and as hereinafter described. What I regard as new is set forth in the claims.

In the accompanying drawings, which illustrate the apparatus which I prefer to employ and the principal stages in using the same to practice my improved method,—

Fig. 1 is a perspective view of a bosh plate of standard design which may be produced by practicing my invention;

Fig. 2 is a central longitudinal vertical section of the bosh plate as illustrated in Fig. 1 showing the interior construction thereof;

Fig. 3 is a central longitudinal vertical section of the drag with the core pattern in place illustrating the first stage in the operation of forming the mold, the core pattern being partly in section;

Fig. 4 is a similar sectional view showing the assembled cope, drag and core pattern, illustrating the operation of completing the core cavity;

Fig. 5 is a similar sectional view with the core substituted for the core pattern and the parts assembled in horizontal position;

Fig. 6 is a sectional view, taken in the horizontal plane indicated by line 6—6 of Fig. 5, after the flask has been turned to an upright position ready for pouring, some parts of the core being shown in elevation; and

Fig. 7 is a cross-sectional view on line 7—7 of Fig. 6 showing the parts after the cast has been made.

In carrying out my improved process, I employed a flask comprising a drag and a cope which, in the main, are of the usual form, and the core cavity is formed around

a core pattern with the latter in a horizontal position. This is accomplished by placing the core pattern on a follower board, then placing the drag upon the follower board and filling the drag with green sand which is rammed or otherwise suitably compacted over and around the core pattern. This operation is illustrated in Fig. 3, in which 8 indicates the follower board, 9 the core pattern, and 10 the drag. It will be noted that the follower board 8 is provided with a cavity at its upper side of a depth equal to approximately half the thickness of a bosh plate, and that the core pattern is provided at its larger end with a head or block 11 that extends to the adjoining end of the drag, against which it has a more or less extended bearing. In the illustrations the bosh plate, which is indicated by the reference numeral 12, is approximately flat on one side and is convex on the other side. It also tapers in two directions, its front end 13 being somewhat wider and thicker than its rear end 14. At its front end the bosh plate is provided with the usual openings 15, 16, 17 which are screw-threaded for pipe connections. It is also provided at its front end with handles 18, 19 cast integral therewith, as shown in Fig. 1. So far as my present invention is concerned, the bosh plate may be made of any approved design, although I prefer that shown. Assuming that a bosh plate of the design shown is to be made, the head 11 of the core pattern is offset slightly from the upper surface of said core pattern when it is in the position shown in Fig. 3, as indicated at 20 in said figure, this offset being compensated for by a dry sand print 21 fitted upon what is then the upper surface of the head 11, the print of course being placed in position before the green sand is filled into the drag. Also before filling in the sand one or more rods 22 are set on the upper surface of the core pattern, so that they stand vertically, as illustrated in Fig. 3. The upper surface of the core pattern is provided with recesses 23 to receive the inner ends of said rods, said recesses being of a depth corresponding to the thickness of the wall of the bosh plate, or, in other words, to one half the difference between the thicknesses of the core and core pattern. The rods 22 should be placed at the points where they will serve most efficiently to hold the core in place in the

manner hereinafter described, but that may be safely left to the discretion of the molder. The same is true as to the number of rods to be used. These rods are applied before the sand in the drag is compacted, and after the ramming operation they are held firmly in position by the sand. They are made long enough so that after the drag has been filled with sand their outer ends project far enough so that they may readily be grasped and moved endwise. To this end they extend through the usual bottom board 24, indicated by dotted lines in Fig. 3 and by full lines in Fig. 4. After the drag has been rammed and the bottom board 24 applied thereto the assembled parts are turned over, after which the follower board 8 is removed, leaving the core pattern in place on the upper surface of the sand in the drag. The cope 25 is then applied to the drag and secured thereto in any suitable way, after which one or more rods 26 are applied to the opposite side of the core pattern, as illustrated in Fig. 4. I do not consider it necessary, however, to provide that side of the core pattern with recesses to receive the inner ends of the rod or rods 26, although they may be provided if preferred. The cope is then filled with green sand, which is rammed or otherwise compacted over the core pattern and around the rod or rods 26, the position of the parts when this has been done being illustrated in Fig. 4. After the application of a bottom board 27 to the cope, which bottom board is also provided with holes for the passage of the rod or rods 26, the cope is removed to expose the core pattern, which is then removed leaving the inner ends of the rods 22 projecting into that portion of the mold cavity formed in the sand of the drag to an extent equal to the thickness of the walls of the bosh plate to be produced. A dry sand core 28, formed in any suitable way, is then placed in the core cavity of the drag, its under side resting on the inner ends of the rods 22. Said core is also provided with a head 29, corresponding in shape and dimensions to the head 11, said head 29 resting on the dry sand print 21, shown in Fig. 5. The cope is then applied to the drag, and the rod or rods 26 are moved inward until they engage the upper surface of the core 28, as also shown in Fig. 5. The outer end of the head 29 bears against one end of the flask opposite the meeting edges of the drag and cope, and it is held against the end boards 30, 31 of the drag and cope respectively, so that the core cannot move endwise, by any suitable means, such as wires 32 secured at their inner ends to rods 33, 34 imbedded in the head 29, as shown in Fig. 6, and passing out between the meeting edges of the end boards 30, 31 where they are secured to a cross-bar 35 shown in Figs. 5, 6

and 7. The flask is then turned to an upright position such that the head 29 of the core is uppermost, as illustrated in Figs. 6 and 7, the core being then suspended by the wires 32 from the cross-bar 35. During this turning movement the core 28 will be held in its proper position by the rods 22, 26, so that it cannot move sidewise, thereby ensuring that the walls of the bosh plate will be of uniform thickness. After the flask has been turned to its upright position, and before the pouring operation, the rods 22, 26 are pulled out far enough so that their inner ends are withdrawn slightly into the sand of the mold, as illustrated in Fig. 7, leaving shallow recesses or depressions in the inner face of the mold that communicate with the mold cavity. The apparatus is then ready for pouring. Molten copper, or such other metal as may be used in the manufacture of the bosh plate, is introduced through a sprue 36 formed in the mold in the usual way and communicating with the mold cavity by one or more gates 37. I prefer to provide three gates at different heights, as illustrated in Fig. 6, but my invention is not limited to placing them at any particular points. The metal flowing into the mold cavity will form the bosh plate, and also will enter the recesses left by the partial withdrawal of the rods 22, 26, so that the bosh plate as cast will have corresponding bosses 40 on its opposite surfaces, and these are preferably removed in the finishing operation. It will be understood, of course, that the usual sand prints 38, 39 are applied to the head 29 of the core to provide for the formation of the handles 18, 19.

From the foregoing description it will be seen that according to my improved method the mold is completed with the flask in its normal or horizontal position and the core also in horizontal position, in which position it is held by the rods 22, 26, and that the flask is then turned to an upright position, so that the core is then vertical, after which the rods 22, 26 are withdrawn to leave the mold cavity unobstructed with the core suspended from what is then the upper end of the flask. Ordinarily the core will be sufficiently held against lateral movement after the withdrawal of said rods, by the extended engagement of the head 29 with the end members of the flask, but if it be desired to hold the lower portion of the core more firmly against lateral movement, one or more small copper rods may be extended down into the core from the head 29 to near the lower end thereof. When the cast has been made, such rods will pass through the transverse baffles 41, and if it is desired to provide for the removal of the rods after the bosh plate has been completed, by winding them with asbestos at the points where

such baffles will come, and also at such other points as metal will flow around them in making the cast, they may easily be removed after the bosh plate has been formed.

5 So far as I am aware, I am the first in the art to form a mold for bosh plates and similar castings by fashioning the mold cavity with the core in a horizontal position, and then turning the flask so that the core is 10 brought to a vertical position, meanwhile holding the core in its proper position by means extending into the mold cavity, into engagement with the core, and capable of being withdrawn before the cast is made, so 15 as to leave the mold cavity unobstructed, and therefore my invention includes that mode of operation broadly, as well as the apparatus by which it may be practiced. I also believe myself to be the first in the art to 20 position the core by the use of removable positioning devices that extend into the core cavity while it is being formed and are capable of being withdrawn after the mold is completed and before the cast is made, 25 While I prefer to make the cast with the core suspended from the upper end of the flask as described, broadly considered my invention also includes making the cast with the position of the core reversed so that the 30 head 29 is at the bottom instead of at the top of the flask. It should be understood, also, that while my invention is designed primarily for the casting of bosh plates, it 35 may be applied to the casting of any other articles for which it may be suitable. The claims hereinafter made are therefore to be construed accordingly.

In the drawings I have not shown the binding wires that are usually imbedded in 40 the core to strengthen it and hold it together, as the use of such wires has been common practice for many years, and is well understood by those familiar with the art; moreover, the manner in which the core itself is made has nothing to do with my invention, which contemplates the making of 45 the core in any suitable way.

While I prefer to practice my improved process by the use of the apparatus described, I wish it to be understood that any other suitable apparatus may be employed.

What I claim as my invention and desire to secure by Letters Patent, is—

1. The method of casting hollow articles 55 in a flask comprising a drag and a cope which consists in forming a mold cavity containing a core disposed horizontally, with means projecting into the mold cavity for positioning the core, turning the flask to carry the core to an upright position, withdrawing said core positioning means from the mold cavity, and making the cast with the core in an upright position.

2. The method of casting hollow articles 60 in a flask comprising a drag and a cope,

which consists in forming a core cavity in the flask by means of a core pattern, with removable means projecting into said core cavity adapted to position a core therein, substituting a core for the core pattern to 70 form a mold cavity, withdrawing said positioning means from the mold cavity while the core is in an upright position, and making the cast with the core in an upright position. 75

3. The method of casting hollow articles in a flask comprising a drag and a cope, which consists in forming a core cavity in the flask by means of a core pattern arranged horizontally, with removable means 80 projecting into said core cavity adapted to position a core therein, substituting a core for the core pattern to form a mold cavity, turning the flask to carry the core to an upright position, withdrawing the positioning 85 means from the mold cavity, and then making the cast with the core in such upright position.

4. The method of casting hollow articles in a flask comprising a drag and a cope, 90 which consists in forming a part of a core cavity in the drag by means of a core pattern with core positioning means projecting through the drag into such core cavity, applying the cope to the drag and completing 95 the core cavity over the core pattern, substituting a core for the core pattern, closing the flask over the core to form a mold cavity, withdrawing said positioning means from the mold cavity, and making the cast with 100 the core in an upright position.

5. The method of casting hollow articles in a flask comprising a drag and a cope which consists in forming a part of a core cavity in the drag by means of a core pattern disposed horizontally, with core positioning means projecting through the drag into such core cavity, applying the cope to the drag and completing the core cavity over the core pattern, substituting a core for the core pattern, closing the flask over the core 105 to form a mold cavity, turning the flask to carry the core to an upright position, withdrawing said positioning means from the mold cavity, and then making the cast with 110 the core in an upright position.

6. The method of casting hollow articles in a flask comprising a drag and a cope which consists in forming a part of a core cavity in one member of the flask by means 115 of a core pattern having recesses in one surface thereof corresponding in depth with the thickness of the proximate wall of the casting to be made, projecting core positioning means through said flask member into said recesses, completing the core cavity over the core pattern, substituting a core for the core pattern, closing the flask over the core to form a mold cavity, withdrawing said 120 positioning means from the mold cavity and 125

making the cast with the core in an upright position.

7. The method of casting hollow articles in a flask comprising a drag and a cope which consists in forming a part of the core cavity in the drag by means of a core pattern disposed horizontally, with core positioning means projecting through the drag into such core cavity, applying the cope to the drag and completing the core cavity over the core pattern, substituting a core for the core pattern, closing the flask over the core to form a mold cavity, projecting core positioning means through the cope into engagement with the proximate wall of the core, turning the flask to carry the core to an upright position, withdrawing the positioning means from the mold cavity, and then making the cast with the core in such upright position.
- 10 8. The method of casting hollow articles in a flask comprising a drag and a cope which consists in forming a part of a core cavity in the drag by means of a core pattern disposed horizontally and having recesses in one surface thereof corresponding in depth to the thickness of the proximate

wall of the casting to be made, projecting core positioning means through the drag into said recesses, applying the cope to the drag and completing the core cavity over the core pattern, substituting a core for the core pattern, closing the flask over the core to form a mold cavity, projecting core positioning means through the cope into engagement with the proximate wall of the core, turning the flask to carry the core to an upright position, withdrawing the positioning means from the mold cavity, and then making the cast with the core in such upright position.

9. The method of casting hollow articles in a flask comprising a drag and a cope which consists in forming a mold cavity containing a core disposed horizontally, with means projecting into the mold cavity for positioning the core, attaching one end of the core to one end of the flask, turning the flask to carry the core to an upright position in suspension from the upper end of the flask, withdrawing the positioning means from the mold cavity, and making the cast with the core in such upright position.

EDWIN E. SMEETH.
